BOTTLE STOPPER FOR THE STORING OF
STERILE LIQUIDSNaurice M. Nessel, Glenview, Ill., assignor to
Baxter Laboratories, Inc., Glenview, Ill., a cor-
poration of Delaware

Application March 10, 1938, Serial No. 195,193

4 Claims. (Cl. 215—47)

My invention relates to means and methods of storing sterile liquids, such as, for example, parenteral solutions.

An object of the invention is to provide a container closure whereby the sterile solutions may be maintained sterile for long periods of time and preferably from which such solutions may be administered. A further object is to provide a means and method whereby sterile solutions may be maintained over long periods of time under partial vacuum without being visibly contaminated from the closure. A further object is to provide a container with a closure which effectively seals the same while at the same time being readily removed therefrom to permit cleaning the container for subsequent reuse. A still further object is to provide a closure for use with a container for sterile solutions, the closure being resilient, adherent and resistant to the action of chemicals while at the same time having a minimum rubber odor or taste. Other specific objects and advantages will appear as the specification proceeds.

The invention is illustrated, in a preferred embodiment, by the accompanying drawing, in which—

Figure 1 is a perspective view of a container and closure therefor embodying my invention; Fig. 2, a greatly magnified sectional view of a portion of the rubber closure showing the skin formed thereon; and Fig. 3, a sectional view of a modified form of the invention.

In the illustration given in Figs. 1 and 2, the reference character A designates a container equipped with an open neck 10; and B designates a resilient closure therefor.

The container A may be of any suitable construction. In the illustration given, it consists of a glass bottle having an open neck, the neck being provided with beads 11.

The closure member B may also be of any suitable construction and material. In the illustration given, the plug B is formed of rubber and is provided at its top with an annular flange 12. The plug is provided with openings 13 and 14, the opening 14 being suitable for the attachment of an outlet tube for the draining of the contents of the bottle when the same is inverted. The passage 13 is adapted to receive a tube 15 which extends almost to the opposite end of the bottle.

Over the closure B there is a flexible seal C. Any suitable cap for enclosing the members B and C and maintaining them in sealing position may be employed. In the illustration given, I provide an inner metal cap member 16 which extends

about the lower bead 11 and a short distance over the resilient sealing member C. A metal disk 17 is placed over the inner ring 16 and the member C and is confined in position by an outer metal cap 18 which extends about the lower bead 11. 5 The outer cap is provided with a pull tab 19 which may be drawn to sever the outer cap and permit access to the metal disk 17 and flexible seal C.

I make no claim to the foregoing structure 10 except as modified in accordance with the following means and steps.

In the use of a rubber closure in connection with a container as above described, and particularly where partial vacuum is employed, it is 15 found that particles separate from the closure and enter the solution and are ascertainable by visual inspection and may be further identified by chemical means. Solutions containing such small particles and shipped in such containers 20 have been on the market for many years and no means has as yet been devised for eliminating the foreign matter while at the same time maintaining a satisfactory closure. Furthermore, the rubber odor and taste, while undoubtedly innocuous, 25 is objectionable from an esthetic point of view and the removal thereof has been long desired. Furthermore, in the reuse of the container, difficulty has been experienced in removing the rubber closure which has to be seated tightly within 30 the bottle neck to make a perfect seal, and a closure having the capacity of forming a tight seal while at the same time being removable from the container with little effort is very desirable.

I have discovered that a closure may be formed for such a container which will have the properties above described as desirable while at the same time having none of the disadvantages mentioned. I find that a closure plug having a 40 thin skin on the outside thereof can be employed with the container so as to form a tight seal therewith while at the same time being readily removable when it is desired to clean the container for reuse. At the same time, I find that the 45 skin on the plug renders it resistant to the solutions and prevents the formation of particles in the solutions while at the same time greatly reducing the rubber odor and taste. In the illustration given in Fig. 2, the body of the plug B 50 is indicated by the numeral 20 and the thin skin formed is indicated by the numeral 21.

The protective skin having the characteristics above described may be formed in any suitable way. The skin is formed preferably by modify- 55

ing the outer surface of the rubber by chemical means so as to produce a skin of greater specific gravity than the inner portion of the plug while at the same time increasing the molecular weight 5 of the isoprene nucleus and its polymers. The skin is also much smoother and presents a practically unbroken and even surface. This smooth surface permits the plug to be readily drawn out of the neck of the bottle while at the same time 10 its smooth contour forms a uniform seal when pressed into position. This also facilitates the insertion of the plug into position.

A skin having the above characteristics may be formed on the plug itself by treatment of 15 the plug with chemicals or it may be formed as a thin membrane or coating and then drawn or otherwise applied to the exterior of the plug. The coating may also be formed by dissolving modified rubber or rubber-like substances and 20 spraying or brushing or otherwise applying the solution to the plug and then allowing the solvent to evaporate. It will be observed that the new structure formed consists of an inner core portion 20 which is relatively porous and an outer skin portion 21 which is relatively non-porous. In the modification of the rubber to 25 form the skin or modified surface, I believe that the treatment results in polymers of isoprene or polymers of modified isoprene of greater molecular weight and consisting of more units than 30 previously existed in the unmodified structure. This would seem to be substantiated by the fact that it offers resistance to the passage of rubber odor and taste from within the plug to the 35 surface and is therefore obviously less pervious to the passage of substances from the inner portion of the stopper to the extreme surface as well as the passage of water into the plug. While the untreated portion of the plug is often found to 40 take up water with a resultant swelling thereof, I find that the treated skin portion absorbs no water whatever and does not increase in size. While I have illustrated the plug B as being 45 formed of an inner rubber body provided with an integral skin surface, it is also true that the inner body may be formed of other materials, such as, porcelain, glass, etc., and the same may be covered by the skin or modified rubber surface described. In the preparation of such a plug, 50 the treated rubber is preferably dissolved and applied upon the body, being dried thereon by the evaporation of the solvent. In the illustration given in Fig. 3, the reference numeral 22 designates an inner body member formed of 55 glass, and the reference numeral 23 designates a rubber skin of the character described enclosing the body, the skin being preferably thicker than heretofore described to provide the desired resilience. The surface of the glass is preferably 60 rough so as to grip the rubber skin 23.

In the forming of the skin, it will be obvious to those skilled in the art that various methods may be employed. For example, the plug itself may be treated with any of the halogens for a period 65 of time so as to form the halogenated rubber crust or skin. Any suitable means for applying chlorine, fluorine, bromine or iodine may be used, it being important, however, that the quantities used be limited to prevent a possible toxic effect, 70 particularly with fluorine, bromine and iodine. Of the foregoing, I have found chlorine most satisfactory. Also, the skin may be formed, as is well known to those skilled in the art, by the addition of sulphur or compounds of sulphur with 75

the halogens. For example, the sulphur may be added by vulcanizing the outer surface of the plug or by treatment with a solvent containing sulphur or compounds of sulphur with the halogens. The use of sulphur in compounds with one 5 of the halogens may result in the addition of said compounds to the isoprene nucleus or polymers thereof.

As a specific example of the process or means, I may set forth the following: The formulated 10 plug is immersed in water saturated with chlorine at above or below room temperature for a period of four minutes. After the above period of immersion, the action of the chlorine-saturated water upon said plug is stopped by a suitable means, 15 namely by rinsing in water or by immersing for a period of four minutes in a solution of sodium thiosulphate, sodium hydroxide, sodium carbonate, or any other alkaline solution, or in a solution of sodium nitrite or the nitrite radical compounded with any other suitable radical or metal. If the action of the chlorine is stopped by means other than water, it is necessary to wash the stopper after treatment with any of said anti-chlor so as to prevent them from coming in 20 contact with the sterile solutions thereby avoiding any toxic effect which might come from such use.

In the forming of the closure described, I treat 25 the resilient seal C in exactly the same manner as above described. However, by reason of the thinness of the seal, the satisfactory treatment with the chlorine-saturated water can be accomplished in about a minute. The thin seal C after 30 treatment has the above described beneficial characteristics mentioned with respect to the plug. The skin formed thereon lies against the smooth top surface of the plug forming a tight seal there-with while at the same time being readily removable when it is desired to open the container. 35 Likewise, the treated seal aids in preventing the formation of foreign bodies in the solution. By having a plug provided with a smooth skin and a seal also provided with a similar skin, a very 40 satisfactory and efficient closure is provided for 45 the container. If desired, the entire plug or seal or the rubber portion thereof may be fabricated from chlorinated rubber or halogenated rubber, or of rubber to which has been added compounds of sulphur with the halogens. 50

While in the foregoing description, I have set forth specific means and methods for producing the desired skin or modified surface upon the plug and flexible seal, it will be understood by those skilled in the art that many equivalent methods 55 may be employed, and such equivalent methods may obviously be used without departing from the spirit of my invention.

The foregoing detailed description has been given for clearness of understanding only and no 60 unnecessary limitations should be understood therefrom, but the appended claims should be construed as broadly as permissible in view of the prior art.

I claim:

1. In combination with a container having an open neck, a closure plug engaging said neck and having at least one passage through the plug, and a resilient seal above said plug, said plug and seal being formed of rubber, the outer surface 70 portion of which is halogenated to provide a smooth rubber skin.

2. In combination with a container having an open neck, closure means therefor, said closure means including a rubber plug member engaging 75

said neck and having at least one passage therethrough, and a resilient seal member above said plug adapted to close said passage and to maintain a partial vacuum within said container, said members being formed of rubber, the inner portion of which is substantially unmodified and the outer portion of which is halogenated to provide a smooth skin thereon.

3. In combination with a container having an opening therein, a rubber plug for said opening,

said rubber plug having at least the lower portion thereof chlorinated to increase the molecular weight of the isoprene and its polymer constituents, the interior of the plug being substantially unmodified by contact with chlorine.

4. A stopper for a container, comprising a rubber body having a non-halogenated interior core portion and an outer halogenated skin portion integral with said core portion.

NAURICE M. NESSET. 10
